William C. Coleman
BY
Arthur C. Brown
ATTORNEY

UNITED STATES PATENT OFFICE.

WILLIAM C. COLEMAN, OF WICHITA, KANSAS.

CENTRIFUGAL MACHINE.

Application filed August 6, 1923. Serial No. 656,102.

To all whom it may concern:

Be it known that I, WILLIAM C. COLEMAN, a citizen of the United States, residing at Wichita, in the county of Sedgwick and 5 State of Kansas, have invented certain new and useful Improvements in Centrifugal Machines; and I do declare the following to be a full, clear, and exact description of the invention, such as will enable others 10 skilled in the art to which it appertains to make and use the same, reference being had to the accompanying drawings, and to the figures of reference marked thereon, which form a part of this specification.

15 This invention relates to centrifugal separators, and the primary object is to provide a simple, efficient form of separator, whereby a body of mercury may be contained within the machine and co-related therewith 20 so that the mercury can take out the metal, the demetalized sludge or pulp being passed on through the machine and the mercury subsequently treated to recover the metal contained therein.

25 The novel construction of the invention will be apparent by reference to the following description in connection with the accompanying drawings in which:

Fig. 1 is a vertical longitudinal, 30 sectional view through a separator constructed in accordance with my invention, and Fig. 2 is a sectional view on the line 2—2 of Fig. 1.

In Fig. 1, I have shown the machine as a 35 two unit machine, both units being, to all intents and purposes, duplicates. Therefore, I will refer to the units generically and specifically describe one of them.

The units 1 and 2 are fastened together 40 by bolts 3. The unit 1 differs from the unit 2 in that it is provided with a cover plate and a hollow shaft for supporting it. The hollow shaft will either be stationary or driven; if driven, suitable mechanism will 45 be provided for that purpose. The unit may be specifically described as a cylindrical casing having a bottom 4 with a depending threaded collar 5, surrounding a discharge opening 6. The top edge of the cylindrical 50 wall of the casing 1 is provided with an outstanding flange 7. At the juncture of the flange with the wall of the cylindrical casing is a shoulder 8 to receive a packing ring 9, upon which may rest the cover plate 10. The cover plate also rests on the flange 55 7, and it is fixed thereto by the bolts 11.

At the center of the cover plate is a depending collar 12, extending into the unit, and it surrounds a central inlet opening 13, by means of which ore may be fed into the machine, preferably through the hollow shaft 14, which is fastened to the threaded collar 15, extending upwardly from the plate, 10. The hollow shaft 14 may be a driving shaft for the unit 1, and, of course, if the unit 1 is driven, the casing for the unit 2 will be driven, because the unit 2 is fastened to the unit 1 by the bolts 3. The depending collar 12 carries a distributor, consisting of a hollow hub 16, which is 60 threaded to the collar 12. The hollow hub extends downwardly within the casing and the unit 1, and it is provided with circumferential, lateral flanges 17 and 18 which extend to points adjacent the separating space 19 in juxtaposition to the body of mercury 20, in the cup shaped separator 21. The cup shaped separator 21 is keyed to a central shaft 22, which extends through both units and which extends through the unit 1, if one unit is used, and through both units if two units are used. Obviously, the units may be multiplied to whatever extent is desired. The mercury containing separator 75 cup 21 is shown as secured to the shaft 22 by a key 23, but any other suitable means may be employed if desired. The bottom of the separator cup is separated from the bottom flange 18 so that material entering 80 through the shaft 14 can pass to the bottom, and since the shaft 22 is a rotating shaft, the centrifugal force within the cup shaped separator 21 will draw the sludge toward the periphery of the separator cup and cause it to flow over the mercury 20, and inasmuch as mercury has an affinity for metal, 85 the metal will be absorbed by the mercury, and the sludge, demetalized, will pass through the opening formed by the inturned flange 24, then downwardly through the space 25 and finally out through the discharge 6, where, if two units are employed, it will be subjected to the same action in the second unit, since the second unit conforms 90 to the first, and, obviously, if a third unit is employed, the operation will be repeated.

The first unit constitutes a cover plate for the second unit. It will be noted here that the only difference between the second unit and the first is that the bottom 4 takes 95 the place of the cover plate 10 for the second unit. Therefore, the machine can be con-

structed for a single unit machine or a multiple unit machine without deviating from the structure of parts; i. e., the parts are all interchangeable, and if it is desired to use 5 the second unit as a single unit, it will be necessary only to remove it from the first unit and place a cover plate like 10 thereon. Obviously, after the machine has been operated for a while, the mercury will reach a 10 saturation point, because it will take up as much metal as it is capable of absorbing. When it is desired to draw off the mercury, this can be accomplished by taking out the plug 26 in the first unit and the plug 27 in 15 the second unit. The mercury can then be treated to recover the metal. When the metal is recovered, the mercury can again be used in the machine.

With the construction herein illustrated, 20 the separator need not necessarily be operated in a vertical position as shown. It can operate at various angles and horizontally.

While I have specifically described the 25 various details of construction illustrated, I do not wish to be limited to the exact embodiments shown.

What I claim and desire to secure by Letters-Patent is:

1. A centrifugal separator comprising an 30 outer casing, an inner casing and a distributor supported by the outer casing, but located wholly within the inner casing, and means for imparting relative movement to one of the casings with respect to the other.
2. A centrifugal separator comprising an 35 outer casing, an inner casing and a distributor

40 utor within the inner casing driven by the outer casing, and means for effecting rotative movement of one casing with respect to the other.

45 3. A centrifugal separator comprising an inner casing, an outer casing, a distributor within the inner casing, having peripheral flanges, a mercurial column in the inner casing, bridging the space between the flanges, means for feeding material into the inner casing, the inner casing having an outlet at its top, the outer casing having an outlet at the bottom, and means for causing relative movement between the two casings.

50 4. A centrifugal separator comprising an inner rotor, an outer rotor, independent means for driving the rotors and a distributor supported by the outer casing and located wholly within the inner casing.

55 5. A centrifugal separator comprising an inner rotor, an outer rotor, a distributor within the inner rotor, means for independently driving the two rotors, and means for driving the distributor at the same speed as the outer rotor.

60 6. A centrifugal separator comprising an inner rotor, an outer rotor, a rotatable distributor within the inner rotor, means for feeding material into the inner rotor, the inner rotor having an outlet at its top, and the outer rotor having an outlet at its bottom.

65 In testimony whereof I affix my signature.

WILLIAM C. COLEMAN.
